ATTORNEY

UNITED STATES PATENT OFFICE.

JOHN S. McWHIRTER, OF NEW YORK, N. Y., ASSIGNOR TO WESTINGHOUSE ELECTRIC & MANUFACTURING COMPANY, A CORPORATION OF PENNSYLVANIA.

CONTROL APPARATUS.

Application filed June 9, 1919. Serial No. 302,663.

To all whom it may concern:

Be it known that I, JOHN S. McWHIRTER, a citizen of the United States, and a resident of New York, in the county of New York 5 and State of New York, have invented a new and useful Improvement in Control Apparatus, of which the following is a specification.

My invention relates to control apparatus 10 for dynamo-electric machines and it has special relation to platform controllers upon electric railway vehicles for governing both the electric circuits and the air-brake apparatus.

One object of my invention is to provide, 15 in conjunction with a platform controller, remotely-located foot-operated means whereby a step-by-step movement of the controller drum may be effected in accordance with the movements of the motorman's foot.

Another object of my invention is to provide an apparatus of the above-indicated character wherein a pawl-and-ratchet device is provided for effecting a step-by-step 20 movement of the drum controller in a forward direction under the control of a foot-operated member, together with a suitable spring device for automatically returning the apparatus to the initial position when 25 the foot-operated member is relieved of pressure.

A further object of my invention is to mechanically couple an engineer's valve or other brake-controlling means with the foot-controlled device for the electric controller, 30 whereby the brake-controlling means is operated during only a portion of the drum travel to effect release of the brakes before the electric circuits are closed and to effect 35 the application of the brakes after the electric circuits have been opened.

Further objects of my invention will become evident from the following detailed 40 description taken in conjunction with the accompanying drawing, wherein—

Figure 1 is a view, in front elevation, of a complete control apparatus constructed in accordance with my present invention;

Fig. 2 is an enlarged plan view of the air-brake controlling means that is shown in Fig. 1;

Fig. 3 is a view, in side elevation, of a

corresponding portion of the brake-control apparatus;

Fig. 4 is an enlarged plan view of the 55 foot-operated device that is shown in Fig. 1; and

Fig. 5 is a view, in longitudinal section, of the structure shown in Fig. 4.

Referring to Fig. 1 of the drawing, the 60 structure here shown comprises a platform controller 1 of the familiar "K" type; a brake-controlling means 2 in the form of the well-known engineer's valve; and a foot-operated device 3 and power-transmitting 65 mechanism 4 for operatively connecting the controller and the engineer's valve under predetermined operating conditions.

The controller 1 comprises the usual encasing member 12 and top cover member 13 70 that are adapted to enclose a rotatable drum 14, having an upwardly-extending operating shaft 15, for arranging the circuits of the railway motors or other apparatus to be controlled and to also enclose the usual reverser drum 16, which is provided with an upwardly-extending shaft 17, to the outer end of which the customary reverse lever 18 is attached.

A suitable bracket or standard 19 is secured to the encasing member 12, for example, and is provided, near its upper end, with a bearing or journal 19a, with which a plurality of other bearing members 20, 21 and 22 are aligned, being suitably secured to 80 the vertical walls of the vehicle vestibule, for example. A shaft 23 is rotatively mounted within the several bearing members, thus extending transversely of the upwardly-extending shaft 15 for the drum controller 14. 90 A bevel gear-wheel 24 is secured to the outer end of the shaft 15 to mesh with a second bevel gear-wheel 25 that is attached to the transversely-extending shaft 23.

The right-hand end of the shaft 23 is provided with a bevel gear-wheel 26, only a portion of which is provided with teeth, as clearly illustrated in Fig. 3, and such portion meshes with a bevel pinion 27 which is secured to the operating stem 28 for the engineer's valve 2.

The valve 2 may be of any well-known type, comprising essentially a suitably chambered cylinder 29, with which a plurality of

supply and outlet pipes 30 communicate, and an operating handle 31 which is attached to the operating stem 28, for permitting hand operation of the valve whenever desired.

5 For the purpose of biasing or automatically returning the various rotatable members to the illustrated initial positions, a suitable spring 32 encloses a portion of the transversely-extending shaft 23, the ends of 10 the spring being secured to that shaft and to the bearing member 21, respectively. It will be understood, however, that any other suitable or convenient means for biasing the apparatus towards the illustrated position 15 may be utilized.

As indicated in Fig. 2 and Fig. 3, the engineer's valve 2 is adapted to assume four operative positions E, S, L and R, respectively standing for emergency-brake application, service-brake application, lap and brake release. The biasing spring 32 normally maintains the engineer's valve 2 in the emergency-braking position E, as clearly 20 shown in Fig. 2. In this way, upon incapacitation or intention of the motorman, an emergency-braking application is automatically made to rapidly bring the vehicle to rest, which is particularly desirable in the case of "one-man" or "safety" cars, to which 25 my invention may be applied with especially 30 advantageous results.

The toothed or operative portions of the bevel gear-wheels 26 and 27, as illustrated in Fig. 3, cover the range of travel of the engineer's valve 2 from the initial or normal 35 emergency-braking position E to the brake-release position R which also corresponds to the "power on" position of the controller drum 14. The preferred arrangement of 40 parts is such that the vehicle brakes are fully released by the valve 2 just before the control drum 14 reaches its first operative position. Thus, it is necessary to initially 45 position the drum 14 a corresponding distance behind or in the reverse direction from the customarily occupied "off" position of such controllers. In other words, the relative 50 positions of the drum 14, for controlling the electric circuits of the vehicle, and of the engineer's valve 2, for governing the 55 braking apparatus, is such that, upon movement of the foot-operated device 3 in a manner to be set forth, the transversely-extending shaft 23 is operated to first effect movement of the engineer's valve 2 from position 60 E to position R by means of the corresponding notched portions of the bevel gear-wheels 26 and 27 and, as soon as the vehicle brakes have been released, the controller 14, 65 which has been actuated through the same number of open-circuit notches, then assumes its first operative position to apply power to the electric motors to be controlled.

The above-mentioned actuation of the transversely-extending shaft 23 is effected

through the agency of a bevel gear-wheel 33 that is secured to the shaft 23 to mesh with a horizontally-extending bevel gear-wheel 34. The latter gear-wheel is mounted upon a vertical shaft 35 which is maintained 70 in proper alignment by means of an arm or bracket 36 that may be suitably secured to the controller cover 13. The lower end of the shaft 35 is provided with a bevel gear-wheel 37 which meshes with a vertical bevel gear-wheel 38 that is mounted upon the operating shaft 39 of the foot-operated device 3.

The shaft 39 is suitably journaled in the vertical arms of a stand or support 40 to be 80 actuated by the application of the motorman's foot to a pedal or foot-lever 41.

The pedal 41 is provided with a detachable pivotal connection 41a, or the equivalent, with a suitable portion of the stand 40 85 and is biased to the illustrated solid-line position by means of a helical spring 42 that acts between the pedal and the base portion of the stand. The toe of the pedal 41 is detachably secured by a hook connection 43, 90 for example, to a link member 44 having a pivotal connection with an arm or crank member 45, which has an annular opening for surrounding a ratchet member 46 that is rigidly secured to the shaft 39. The crank 95 member 45 is suitably supported or journaled within a plurality of arms 48 that extend from one side of the stand 40, and is provided with a rigidly-mounted pawl or finger 47 that extends within the annular 100 opening of the crank member to engage the successive teeth of the ratchet 46 under operating conditions, as indicated by the dotted-line position of the device.

The pawl 47 may be secured within the interior opening of the crank member 45 by means of a suitable pin, welding or otherwise. It will be understood that the member 45 is mounted eccentrically with respect to the shaft 39, in order to provide the operation outlined above. In this way, the pawl 47 is adapted to effect step-by-step movement of the ratchet 46 as the pedal 41 is depressed, the pawl receding to an inoperative 110 position (shown in full lines) as the pedal 115 is raised.

The actuation of the foot-operated device 3 to produce rotative movement of the vertical shaft 35 and, therefore, of the transversely-extending shaft 23, may be set forth 120 as follows. Upon depression of the pedal 41 by the motorman's foot, the rigidly mounted pawl 47 is brought into engagement with a corresponding tooth of the ratchet 46, which is rotated in a forward direction for one 125 notch as the pedal 41 is depressed to its lowermost position. The shaft 39 of the foot-operating device 3 and, therefore, the bevel gear-wheels 38 and 37 are thus rotatively moved a corresponding distance. 130

Upon upward or return movement of the pedal 41 to the illustrated solid-line position, the pawl 47 recedes to its position, shown in solid lines, near the succeeding ratchet tooth, 5 in readiness for further rotative movement.

In this way, oscillation of the pedal 41 between the illustrated solid line position and the lowermost position effects a step-by-step or intermittent movement of the 10 ratchet 46 as the successive teeth thereof are engaged by the pawl 47, whereby the engineer's valve 2 is first operated from its initial position E to its brake-release position R, whereafter the control drum 14 is 15 likewise moved in a step-by-step manner through its successive positions, the engineer's valve meanwhile remaining in its brake-release position R by reason of the absence of teeth from the corresponding portions of the bevel gear-wheels 26 and 27.

Whenever it is desired to return the illustrated control apparatus to the initial or normal position, either in the regular course of operation or to effect a sudden stop to 25 prevent an accident, for example, the motorman merely removes his foot from the pedal 41, which is thereupon actuated by the spring 42 to the illustrated solid-line position, which movement is accompanied by 30 a disengagement of the pawl 47 from the ratchet 46. Since the pressure between the pawl and the ratchet, which pressure has counteracted the constant biasing tendency of the shaft spring 32, is thus removed, the 35 return movement of the apparatus is immediately and automatically effected by such biasing action of the spring 32. The control drum 14 is thus returned to its "off" or inoperative position just before the 40 notched portions of the bevel gear wheels 26 and 27 mesh to effect movement of the engineer's valve 29 from the brake-release position R to the normal emergency braking position E. In this way, an emergency 45 brake application is automatically effected whenever the pedal 41 is relieved of pressure of the motorman's foot, whether from incapacitation or intention of the motorman.

50 It will be understood that, if desired, the illustrated bevel-gear-wheel arrangement may be replaced, for example, by an equivalent rack-and-pinion device for effecting the desired movements. Furthermore, other 55 modifications in the structural details or arrangement of parts herein illustrated may be effected without departing from the spirit and scope of my invention. Consequently, I do not wish to be restricted to the specific 60 apparatus shown, but desire that only such limitations shall be imposed as are indicated in the appended claims.

I claim as my invention:

1. The combination with a multi-position 65 control element, of a foot-operated mem-

ber, means comprising a pawl-and-ratchet device for ensuring step-by-step movement of said element in a certain direction, and means for automatically effecting return movement of said element. 70

2. The combination with a rotatable control drum having an upwardly-extending shaft, of a foot-operated member located on a materially lower level than said shaft, means comprising a pawl-and-ratchet device 75 for ensuring step-by-step movement of said drum in a forward direction, and means for biasing said drum towards a predetermined position.

3. The combination with a rotatable control drum having an upwardly-extending shaft, of a foot-operated member located on a materially lower level than said shaft, a second shaft extending transversely of the first shaft and geared thereto, means comprising gear-wheels and a pawl-and-ratchet device for connecting said foot-operated member to said second shaft to effect step-by-step forward movement of said drum, and a spring attached to the rotating parts 80 to automatically effect return movement thereof. 85

4. The combination with a rotatable control drum having an upwardly-extending shaft, of a foot-operated member located on a materially lower level than said shaft, a second shaft extending transversely of the first shaft and geared thereto, means comprising gear-wheels and a pawl-and-ratchet device and responsive to foot movement of said member for effecting step-by-step operation of said second shaft and said drum, means for biasing said pawl-and-ratchet device to an inoperative position, and means for thereupon returning said 90 drum to its initial position. 95

5. The combination with a multi-position control element, of a foot-operated member, means for ensuring a step-by-step movement of said element in accordance with the movements of said member, and means for biasing said element to an inoperative position. 100

6. The combination with a rotatable control drum, of a foot-operated member, power-transmitting mechanism for co-operatively connecting said drum and said member under operating conditions, and means biased to normally disconnect said member from said mechanism. 115

7. The combination with a multi-position control element, of a foot-operated member, means comprising a pawl-and-ratchet device for effecting step-by-step movement of said element in a certain direction, means biased to normally disconnect said member from said device, and means dependent upon such disconnection for effecting return movement of said element. 120

8. In a system of vehicle control, the 125

- combination with a multi-position control element, of a foot-operated member, means for ensuring a step-by-step movement of said element in accordance with the movements of said member, and brake-controlling means for the vehicle also governed by said foot-operated member.
9. In a system of vehicle control, the combination with a rotatable control drum, of a foot-operated member, power transmitting mechanism for co-operatively connecting said drum and said member, and air brake-controlling means for the vehicle also governed by said mechanism.
10. In a system of vehicle control, the combination with a multi-position control element, of a foot-operated member, means comprising a pawl-and-ratchet device for ensuring step-by-step movement of said element in a certain direction, means for automatically effecting return movement of said element, and brake-controlling means for the vehicle actuatable with said element during a portion of the travel thereof.
11. In a system of vehicle control, the combination with a rotatable control drum having an upwardly-extending shaft, of a foot-operated member located on a materially lower level than said shaft, means including a plurality of gear-wheels for operatively connecting said shaft and said member, brake-controlling means for the vehicle, and means comprising a plurality of gear-wheels for connecting said brake-controlling means to said member during a portion of the drum travel.
12. In a system of vehicle control, the combination with a rotatable control drum having an upwardly-extending shaft, of a foot operated member located on a materially lower level than said shaft, a second shaft extending transversely of the first shaft and geared thereto, means comprising gear-wheels and a pawl-and-ratchet device and responsive to foot-movement of said member for effecting step-by-step operation of said second shaft and said drum, brake-controlling means for the vehicle, means for effecting movement of said brake-controlling means during a portion of the drum travel, means for biasing said pawl-and-

ratchet device to an inoperative position, and means for thereupon returning said drum and said brake-controlling means to their initial positions.

13. In a system of vehicle control, the combination with a multi-position control element, of a foot-operated member for ensuring step-by-step movement of said element, brake-controlling means for the vehicle also governed by said member, and means for biasing the control element to an inoperative position and the brake-controlling means to an operative position.

14. In a system of vehicle control, the combination with a rotatable control drum, of a foot-operated member, power-transmitting mechanism for co-operatively connecting said drum and said member, brake-controlling means for the vehicle also actuated by said mechanism during the initial forward or final backward travel of said drum, and means for biasing said brake-controlling means and said drum to such positions that such initial forward travel corresponds to open-circuit condition of the drum.

15. In a system of vehicle control, the combination with a rotatable control drum, of a foot-operated member, air brake-controlling means for the vehicle biased to a brake-application position, and means for effecting concurrent movement of the air brake-controlling means and the control drum, the arrangement of parts being such that the air brake-controlling means occupies its "brake-release" position before the control drum reaches an operative position.

16. In a system of vehicle control, the combination with a rotatable control drum, of a foot-operated member for effecting movement of said drum, air brake-controlling means for the vehicle, and means for operating said controlling means to effect application of the vehicle brakes upon the return of the drum to its normal position.

In testimony whereof, I have hereunto subscribed my name this 16th day of May 1919.

JOHN S. McWHIRTER.
